UNITED STATES PATENT OFFICE

2,114,473

GLASS TILE OR PANEL

Joseph Labra, Long Island City, N. Y.

Application April 30, 1936, Serial No. 77,125

6 Claims.

(Cl. 72—18)

This invention relates to tiles and to the method of applying same to walls, floors and the like and has for one of its objects the provision of a simple, inexpensive yet highly efficient method of preparing and applying such tiles wherever necessary.

Another object of the invention is to affix individual backings to panels or to tiles individually so as to adapt some to be subsequently pasted, cemented, or otherwise secured to the foundation wall. The said process being just as adaptable for panel substitutes made of various rigid or flexible materials as for instance metal, glass, pyroxylin, Celluloid, and the like as it is for ordinary tiles made of clay, glass, porcelain, etc., etc.

A still further object of the invention is the provision of a process for setting tiles which comprises the application of a substantially lightweight aqueous adhesive compound to one or more surfaces of the tile and to the surface of the object against which the tile is intended to be pressed for adhesion, thus avoiding the heavy loads of mortars and stucco materials now commonly used.

Other objects and novel features of my invention will appear as the description progresses.

The disclosure made the basis of exemplifying the present inventive concept suggests a practical embodiment thereof, but the invention is not to be restricted to the exact details of this disclosure, and the latter, therefore, is to be understood from an illustrative, rather than a restrictive standpoint.

The inventive idea involved is capable of receiving a variety of mechanical expressions, one of which, for the purpose of illustration, is shown on the accompanying drawings, in which

Fig. 1 shows a glass sheet provided with an absorbent backing, ready to be attached to a wall or object.

Fig. 2 is a side view thereof.

Fig. 3 is a perspective view of glass panel, having a composite backing of an adhesive mixed with cork granules.

Fig. 4 is a perspective view of a transparent panel or tile made of any suitable glass plate and provided with a backing made of a layer of my adhesive and other intermediary coating of a coloring matter.

Fig. 5 is a perspective view of a modified form of my invention, wherein the adjacent panels interlock with each other.

Fig. 6 is a fragmentary view of an opaque glass plate to which a prepared backing is attached.

Fig. 7 is a top plan view of a base to which the glass sheet may be adhered or cemented.

Fig. 8 is a side view thereof looking from the bottom of Fig. 7.

Fig. 9 is a side view of the combined materials 5 as shown on Figs. 6 and 7, forming the structure.

Fig. 10 is a face view of doublet glass panels secured to an absorbent backing ready to be applied to a wall as decorative panel or border.

Fig. 11 is a side view thereof.

Fig. 12 is a perspective view of an ordinary glass plate with a felt paper backing, ready to be attached to a wall with my adhesive cementing compound.

It is to be understood that the disclosure of this 15 invention also includes the preparation of wall panels and tiles produced from other materials such as herewith disclosed:

The preparation process and manner in producing the proposed composite panels is exactly as described and illustrated in the accompanying drawings and represented in the form of glass. For materials that are liable to twist out of shape by contraction, such as glass, I prefer to use a base sheet made of an absorbent matter such as cardboard, felt paper or the like, which will accelerate the adhesion by quickly absorbing the moistened cementing matters when the panel is applied to the wall or object.

Referring now to the appending claims of the 30 present mural glass structure, it is understood that the interposed film or objective, coloring matters between the facing glass sheet and the backing base, may constitute an imitation marble design as well as any other contemplation that might be practical for a wall panel and the said 35 design may be first applied to the glass by any process (preferably by brush) or that the said coloring matter may be thoroughly mixed therein with the plastic like adhesive as a coloring constituent of the proposed backing.

Again relating to the drawings in detail:

In Figs. 1 and 2, I have shown a composite mural glass panel 41, having a porous or cardboard backing 42, secured therein by a layer of 45 coating 43, of a cementitious compound.

In Fig. 3, I have shown a transparent glass panel 44, and an alkali resisting coloring matter 44a, forming a decorative panel which is being provided with a rough composite backing 45, 50 comprising a glass adhesive mixture containing rubber latex and casein, mixed with sawdust, asbestos fibres, ground cork, or the like materials.

In Fig. 4, I have shown a transparent glass panel or tile 46, made of any suitable sheet of 55

clear glass which is provided with a backing 47, and a coloring matter 47a, having alkali resisting qualities which is interposed between the glass sheet and the attached backing. The said coloring matter may be applied to the back surface of the glass sheet by several methods as taught by the art.

In Fig. 5, I have shown a pair of panels 48, each of which is provided with an end flange 49, a top flange 50, and an undercut 51 and a bottom undercut 52. The flanges 49, of a panel fit into the undercut 51, of the other panel. Likewise the flanges 50, are adapted to fit into the undercuts 52, of a second pair of such panels. The said pair of panels 48, form a panel section 53, which are provided with a suitable backing 54, secured to the panel section by a coating 55, of the adhesive.

In Fig. 6, I have shown a fragmentary view of a surfacing glass plate 24, to which a backing member 22, with a coating of a suitable adhesive 23, is subsequently attached.

In Fig. 7, I have shown a top plan view of a backing base sheet 22, made of any suitable material and prepared with an adhesive coating 23, subsequently and while the cementitious matter is in a moist like condition. A suitable sheet of glass 24, of approximately the same size and shape, is embedded in the said adhesive 23, upon the backing base 22 and both base and surfacing glass sheet are squeezed or pressed to a compact form which results then, become an inseparable part and is ready for application to the object.

In Fig. 8, I have shown the side view of the base sheet looking from the bottom of Fig. 7.

In Fig. 9, I have shown the side view of said combined materials which form the panel, 22 is the backing support of the composite structure, 23 is the adhesive or a combination mixture of an adhesive and coloring matter, 24 is the glass plate secured to the base sheet by said adhesive.

In Fig. 10, I have shown a pair of mural panels 35, which may be made of any desired shape, size, color or variety of materials as indicated in the present disclosure and which are attached to a backing 36, by a coating of an adhesive 37, preferably containing rubber latex and casein.

In Fig. 11, I have shown the side view of the panel sections 38, as shown on Fig. 10, 36 is the backing support of the structure, 37 is the casein latex adhesive and 38 is the surfacing materials.

In this manner, the panel sections 38, formed by the panels 35 and base 36, are used for decorative purposes such as borders or fancy wall panels. A coating of an adhesive being applied to the exposed surface of the backing 36 and to the wall or other support with which the said section is used.

In Fig. 12, I have shown a glass tile 39, which is provided with a backing comprising a mixture of the rubber latex and casein adhesive and a layer of felt paper 48, secured to the tile by the said adhesive.

In this form of my invention I may employ a composition of matters consisting of a large proportion of calcium carbonate, (cal. hydroxide) or other earthy or chemical hydroxides in combination with other desired pigments whether (inert or otherwise). One or a combination of some of the said powdered materials is incorporated into the casein latex adhesive preparation and is all thoroughly mixed to an adhesive of plastic like texture.

Thereafter, one or more layers of said cementitious matter is spread upon one side of the glass plate and a sheet of an ordinary moist absorbing

paper is applied to the plastic upon the glass plate. The said layer of paper will not only assist the drying speed of the moistened adhesive upon the glass but also help the structure when same is applied to the object and again aids in making the plastic surfacing smooth, when placed to dry under a flat object.

In this manner I am able to produce a new and distinctive glistening mural covering structure adaptable to resurface old or new walls and which will permanently retain their new like luster, without the drudgery of polishing or other frequently needed attention.

While other adhesives may be found to be adaptable for the construction of the present composite glass structure, I prefer to use one of my described compositions for the reason of its glass cohesive qualities, its workable plasticity and because of its pure white constituents, which may be easily changed into a variety of colors, by adding oxides or other desired coloring matters.

It is further understood that the conception of this invention particularly involves the process in producing the mentioned structures, regardless of the multitude of materials which may be employed in its construction, or the manner of using the materials.

As an instance, I may use a priming coat of my improved glass like transparent adhesive and other coloring and backing layers of the proposed cementitious plastic or other materials. In this form it will appear that the adhesive will not necessarily be mixed therein, with the said alkali resisting coloring matters but the coloring may be applied after the adhesive upon the glass and is subsequently covered with other layers of the cementitious materials and matters.

The adhesive used for securing or attaching the base sheet to the surface plate or sheet panel or to one individual block simulating a tile, constitutes a water resisting plastic comprising rubber latex, casein and one or all of the following ingredients: sodium carbonate, sodium salicylate, sodium chloride, sodium tungstate, trisodium phosphate, calcium hydroxide, magnesium chloride, ammonia chloride, zinc oxide, oil including an accelerator.

Examples of my method in converting any ordinary tile that is not liable to twist out of shape, by contraction, such as clay, mosaic, asbestos, glass, steel and others: A coat of the compound rubber latex, casein and other ingredients is spread over the back of the original tile, and a second object, as a base, the same shape and size of the tile is applied to the back of the original tile that has just been coated with the compound and both base and tile are squeezed or pressed to a compact form leaving the results under pressure for a few days, after which time the tile and base become an inseparable part and is ready for application. The same adhesive compound is used in the preparation of the wall to receive the tile or panel and to either tile or panel is applied an individual backing base or object, and which tile or panel and base is subsequently and individually pressed to the adhesive prepared wall in the ordinary wall decorative manner.

This backing plate or so-called base, may be made of various materials such as vulcanized plywood, fibre boards, wood fibre boards, and any composition board, or cardboard that will quickly adhere to the wall or object in mind. Burlap materials may also be used.

I have found that a dispersion of asbestos

fibres, sawdust, ground cork, and other such materials over the moist plastic composition as is when just applied to the tile, will give perfect results, and can be used as a substitute for com-
5 position boards.

It will be noted that in all the forms of my invention the tiles are provided with a layer or coat of adhesive which either forms a backing for the tile on which is directly applied to a wall 10 or other support, or acts as a connecting medium between the tile and superposed backing which backing may later be coated with the adhesive compound when applying same to a wall, floor, or other support. It may also be noticed that in 15 all the drawings is shown an individual tile or individual panel pasted to the base sheet and which tile or panel occupies the entire area of the base sheet resulting in one single unity and which unit is then pressed individually to the 20 object, which is being moistened with an adhesive cementing matter.

Having described my invention what I claim as new and desire to secure by Letters Patent is:

1. A decorative glass wall covering panel comprising a sheet of glass and a composite backing member containing a decorative paint and an alkali resisting cohesive compound containing rubber latex and casein, a layer of cementitious material and a dispersion of ground cork there-
25 on.

2. A decorative glass covering panel comprising a sheet of glass and composite backing mem-

ber containing a decorative paint and an alkali resisting cohesive compound a layer of cementitious material and a dispersion of asbestos fibres thereon.

3. A decorative glass wall covering panel comprising a sheet of glass and a composite backing member containing a decorative paint and an alkali resisting cohesive compound containing rubber latex and casein, a layer of cementitious material and a dispersion of wood fibres thereon. 10

4. A decorative glass wall covering tile comprising a sheet of glass and a composite backing member containing a decorative paint and an alkali resisting cohesive compound containing rubber latex and casein, a coat of a cementitious 15 material and a layer of moist absorbing matters thereon.

5. A decorative glass wall covering panel comprising a sheet of glass and a composite backing member containing a decorative paint and an 20 alkali resisting cohesive compound containing rubber latex and casein, a coat of cementitious material and a layer of vulcanized plywood secured thereon.

6. A decorative glass wall covering panel comprising a sheet of glass and a composite backing member containing a decorative paint and an alkali resisting cohesive compound a layer of cementitious matters and a dispersion of moist ab-
25 sorbing material thereon.

JOSEPH LABRA. 30
